METATARSAL CUSHION

Benjamin J. Silver, New York, N. Y.

Application November 20, 1936, Serial No. 111,811

13 Claims. (Cl. 36—71)

The invention relates to a shoe and more particularly to the conformation of the foot engaging surface of the inner sole of a shoe in the region of the ball of the foot and the invention 5 herein disclosed constitutes an improvement and development of the invention disclosed in my co-pending application entitled "Sole modifying inner sole", Serial No. 726,738 filed May 21, 1934.

One of the objects of the invention in this case, 10 as was the primary object in the disclosure in the co-pending application, is to provide an improved form of inner sole contour which in its cooperative relation to cushioned and uncushioned or inelastic sole interiors will provide a distribution 15 of cushioned supports to supplement and tend to preserve the tissue areas beneath the points of pressure from the bone structure of the foot. Particularly, the present disclosure features the distribution of weight upon the heads of the metatarsal bones as received on cushioned areas located and arranged so as to distribute the weight 20 loads over enlarged areas of the sole and thus tend to minimize the localizing of pressure areas or spots within limited areas of the shoe sole.

25 It has been found that in the case of persons who stand for long periods of time on their feet, and particularly in the case of elderly people, the tissues forming the natural cushion at the ball area of the foot becomes thin, loses its elasticity and not infrequently becomes calloused, particularly beneath the head of the second, third and fourth metatarsal bones. It has also 30 been found under such circumstances that the heads of the metatarsal bones tend to separate with increase in age with a resulting tendency 35 to permanently strain and to flatten the bone structure forming what is generally referred to as the metatarsal arch. This distortion in the natural relation of the bone skeleton results in strains 40 on the arch, a weakening of the connecting ligament structure, and the development eventually of serious foot trouble. This tendency to a shifting 45 of the bone framework from its initially correct structural position becomes more pronounced with elevation in the heel portion of some modern types of shoes, particularly women's shoes.

Accordingly the primary object of the present disclosure is to provide a form of shoe and particularly an improved form of ball engaging portion 50 of an inner sole to provide for a cushioning effect in the ball portion of the shoe sole and which cushion will not only supplement and tend to defeat present tendencies towards loss in resiliency in the sole tissues beneath the heads of 55 the metatarsal bones but which will at the same

time tend to resist the lateral spreading of these heads.

Still another object is to provide for a natural setting or impression formed in the inner sole closely approximating the impression left by the 5 foot when walking over semi-soft ground barefooted.

Broadly, this aspect of the invention is attained simply by providing shallow recesses, concavities or pockets, in the cushioning area at the 10 ball portion of the inner sole and which recesses are accurately designed, located and arranged to receive and maintain in their natural relative position the slight protuberances formed in the 15 wearer's sole when standing in correct position to transmit the weight through the heads of the metatarsal bones and particularly through the heads of the three middle metatarsal bones.

The invention has for another object the providing of a depth of cushioning material beneath 20 the recesses so formed equal, or at least substantially equal, to the cushioning effect provided for the sole in the region between the heads of the metatarsal bones and in this way obtain an equality in cushioning effect both immediately beneath 25 the heads of the metatarsal bones as well as in the adjacent region considered transversely of the line of heads.

Another object of the invention is to provide a 30 structure which tends to induce the outer half of the ball area of the foot to incline more naturally towards the outer and stronger side so that when the weight of the body is shifted from heel to ball in the physiology of walking the weight will be thrown to the side which nature intended to 35 receive the weight. The highest point of elevation in the cushion in the preferred embodiment of the invention being just back of the head of the second metatarsal bone not only enhances the effect of the outwardly directed natural tilt 40 but also tends to reduce strain on the inner part of the foot not intended by nature to receive body weight strains.

Various other objects and advantages of the 45 invention will be in part obvious from an inspection of the accompanying drawings and in part will be more fully set forth in the following particular description of two forms of inner soles embodying the invention, and the invention also consists in certain new and novel features of construction and combination of parts hereinafter set forth and claimed.

In the accompanying drawing:

Fig. 1 is a vertical sectional view taken longitudinally through the basic shoe with a sole 55

modifying cushioning insert pad shown in position located with reference to the bone structure at the fore part of the foot shown in side elevation in dotted outline and illustrating a preferred embodiment of the invention:

Fig. 2 is a plan view looking down upon the inner sole of the basic shoe and with the pad insert as shown in Fig. 1, showing in dotted outline the bone structure particularly at the heads of the metatarsal bones;

Fig. 3 is a vertical transverse sectional view taken on the broken line 3-3 of Fig. 1;

Fig. 4 is a perspective view of the cushioning insert shown in the preceding figures and with one edge partly broken away to show the cross sectional configuration of the pad;

Fig. 5 is a view similar to the mid-portion of Fig. 1 showing a slightly modified form of the invention; and

20 Fig. 6 is a transverse sectional view of a modified form of the pad featuring a substantially flat bottom side as viewed along the curved line 6-6 of Fig. 2, in advance of the high point and looking rearwardly.

25 In the drawing and referring first to the basic
shoe construction illustrated in Figs. 1 to 3, there
is shown a conventional form of women's shoe
comprising an outer sole 10, an inner sole 11,
with the edge of the upper 12 secured at its for-
30 ward portion between the soles and at its rear end
secured between the upper sole and the top of
the heel 13. In the region beneath the ball of
the foot, there is located a ball or metatarsal
area supporting pad 14. This pad is somewhat
35 irregularly elliptical in plan as shown in Figs. 2
and 4 and located in the shoe in position to re-
ceive the ball of the foot at its advanced and
relatively wide end. This pad is formed of high-
ly flexible material, such as soft rubber, has an
40 underside 15 substantially flat except in the re-
gion beneath the recesses hereinafter described
and has a flatly arched upper side 16. When
viewed in plan as in Figs. 2 and 4, the pad is
somewhat egg shaped, or differently described, is
45 a flat segment of egg form. The pad is carefully
formed with relation to the bone structure of the
fore part of the foot, it being noted that it en-
tirely underlies practically the entire second,
third and fourth metatarsal bones designated re-
50 spectively 2m, 3m, 4m, leaving the first and fifth
metatarsal designated respectively 1m, 5m, un-
cushioned or substantially so particularly in the
case of the first metatarsal bone 1m.

In the preferred design herein illustrated, the 55 pad has its greatest transverse width or minor diameter in its forward portion and has its forward edge in position sufficiently advanced at least to underlap the heads of the metatarsal bones. Considered lengthwise the pad as herein 60 illustrated extends forwardly a distance just sufficient to underlap the first proximo phalanges, specifically designated in Fig. 2 as $2p^1$, $3p^1$ and $4p^1$, of the second, third and fourth toes, leaving all of the phalanges of the first and fifth toes as 65 well as the second and third phalanges of the second, third and fourth toes uncushioned. In other words there is no intent herein to cushion the toes as a whole but on the contrary to provide for the toes the conventional form of leather support directly on the inner sole or, of course, the inner sole with its usual sock lining not herein 70 shown. Considered rearwardly the pad underlaps the anterior half of each of the shanks of the second, third and fourth metatarsals and as 75 shown in Fig. 1 extends substantially to the

juncture of the tarsal and the middle metatarsal bones.

It is a distinctive feature of this pad that it is provided on its upper surface with three shallow recesses, depressions or pockets, designated 17, 18, 19, located to receive respectively the heads of the metatarsals 2m, 3m and 4m. The pad is so formed with an outlining feathered edge 20 that the two outside half or edge recesses or pockets 21 and 22 are formed at the extreme opposite edges to underlap respectively the inner portions of the heads of the first metatarsal 1m and the fifth metatarsal 5m, leaving the outer edge portions of the ball portion of the foot supported directly on the uncushioned outer edge portions of the inner sole 11 as particularly shown in Fig. 3. The centers of the three interior recesses 17, 18 and 19 and the two outer half recesses 21 and 22 are disposed in a curve which when viewed in plan as in Fig. 2 is the curve defined by the centers of the heads of the five metatarsal bones and defines what has been referred to herein as the minor axis of the pad.

In order to maintain equal thicknesses of cushioning material in the interior portion of the pad, the depressions 17, 18 and 19 are matched respectively by downwardly extending projections 23, 24 and 25, as indicated in Fig. 3, and the top surface of the inner sole 11 is correspondingly recessed to conform to the wavy contour defining the underside of the pad in the area beneath the recesses. In other words the upper surface of the inner sole is provided with three shallow and somewhat irregular circular or perhaps elliptical recesses and two half recesses exactly conforming in shape, relative relation and location as those in the pad. It will be noted from examining opposite sides of the inner sole 11 in Fig. 3 that the extreme edges turn slightly upwardly towards the adjacent sides of the upper and thus forms in effect somewhat flat lateral continuations of the outer half recesses 21 and 22 so that the outer edges of the heads of the first and fifth metatarsal bones are banked against the upturned edges of the leather sole. 40

The pad in this case, as was true of the pad in the above identified application, has its maximum elevation at the point *hp* approximately just back of the head of the second metatarsal bone or close thereto with a gradual decreasing in thickness in all directions from this point of maximum elevation to the feathered edge. 45 50

In the modified showing in Fig. 5, the inner leather sole 26 in the region of the ball of the foot is split slightly below its top surface to form a shallow pocket 27 having a conformation in plan approximating that of the pad 14 hereinbefore described and forming an integral overlapping extremely thin flap 28. A rubber pad 29 corresponding in size and conformation to the pad 14 is permanently cemented to the underside of the flap as indicated in Fig. 5 and disposed so that when the pad is lowered into the pocket 27 and the flap restored to its original position and cemented in place the pad will be sandwiched between the portion of the inner sole defining the bottom of the pocket and the flap 28 and will be in the position with its recesses underlapping the heads of the metatarsal bones as described for the preferred embodiment illustrated in Figs. 1, 2 and 3. It will be noted that when the flap is cemented to the top surface of the rubber pad it will conform to the rubber surface and will thus form the recesses in the flap, one of which recesses is shown at 30 in Fig. 5. form the rubber is concealed from view and there is exposed the usual inner sole with or without the sock lining as may be desired.

Even if the flap should not sink into the recesses in the top surface of the pad as originally constructed, the flap soon sinks into the recesses and itself forms corresponding recesses in its upper surface after the shoe has been worn for a while and the same thing becomes true of the sock lining when simply pasted into position as is usual in such practices. It has also been found in practice that after wearing the shoe for a short time the recesses tend to conform to the contour and relative arrangement of the metatarsal bone heads of the individual user, presumably resulting in a slight compacting of the soft rubber used in the areas of increased pressure and a releasing of the rubber, at least slightly from those areas of less or reduced pressure. Anyhow in use, there is a slight modification and sometimes a deeper recess formed than was originally formed at the factory and with a properly fitted shoe each cushion quickly takes on the peculiarities and forms the complement of the ball portion of the foot of the user.

It is understood that the structure herein illustrated in both forms is a factory produced shoe, but it is within the scope of this disclosure to locate a pad 31 having the top recesses or pockets herein featured but with a smooth underside 32, that is an underside without the protections 23-25 engaging the substantially flat top or slightly concaved top surface of a conventional form of inner sole. In either case the pad is contained in place on the inner sole so that in effect the rubber pad becomes a fixed part of the finished shoe.

The disclosure features the use at the ball portion of the foot of a cushion of limited area and merely of an extent and configuration to provide a cushioning effect located where it will do the most good. The weight of the body in walking is transmitted at least in part through the heads of the middle metatarsal bones and to a less extent through the heads of the outer metatarsal bones. Accordingly the cushioning material in the present disclosure is massed to cushion the body weight shocks at the middle of the pad leaving the outer lateral sides of the ball of the foot largely in engagement with the uncushioned and relatively rigid leather sole as illustrated at opposite sides of the showing in Fig. 3.

While there is the intent to provide maximum elevation just back of the head of the second metatarsal bone and gradual reducing in thickness from this point to a feathered edge, it is not desirable to do anything which might tend to cause the heads to separate from each other or otherwise increase their intervals or natural relative arrangement. The providing of the head receiving recesses in the top surface of the pad or the top surface of the overlapping flap or sock lining has the effect of tying all five heads together and the deeper the heads press into the pad the greater will be the resistance offered by the pad to any tendency of the heads to separate.

I claim:

1. In a shoe, the combination of an outer sole, an inner sole provided at the region of the ball of the foot in its upper surface and spaced from the edges of the sole with a shallow depression, a one piece metatarsal arch pad fitting to said inner sole depression, said pad forming a segment of an egg-shaped form with its major axis extending longitudinally of the shoe and with the

portion forming the minor axis underlapping the heads of the second, third and fourth metatarsal bones and having its opposite edges spaced from the adjacent opposite edges of the inner sole thus leaving the heads of the first and fifth bones at least partially uncushioned, and said pad provided on its upper surface with three shallow, elliptical depressions spaced apart transversely and along the minor axis, and located to receive the portion of the sole of the wearer immediately beneath the heads of the second, third and fourth metatarsal bones and said pad in the parts thereof containing these three depressions being of substantially equal thickness thereby to provide equal cushioning effects under the heads of the three middle metatarsal bones, and said pad having its point of highest elevation located under the shaft of the second metatarsal bone and reducing in elevation gradually in all radial directions from said point and forwardly to a position terminating approximately mid-length of the middle first phalanges.

2. In a shoe, the combination of an outer sole, an inner sole provided at the region of the ball of the foot in its upper surface and spaced from the edges of the sole with a shallow depression, a one piece metatarsal arch pad fitting to said inner sole depression, said pad forming a segment of an egg-shaped form with its major axis extending longitudinally of the shoe and with the portion forming the minor axis underlapping the heads of the second, third and fourth metatarsal bones and having its opposite edges spaced from the adjacent opposite edges of the inner sole thus leaving the heads of the first and fifth bones at least partially uncushioned, and said pad provided on its upper surface with three shallow, elliptical depressions spaced apart transversely and along the minor axis, and located to receive the portion of the sole of the wearer immediately beneath the heads of the second, third and fourth metatarsal bones, and said pad in the parts thereof containing these three depressions being of substantially equal thickness thereby to provide equal cushioning effects under the heads of the three middle metatarsal bones.

3. An inner sole for a shoe having a cushioned area of less width than the inner sole, extending longitudinally of the shoe in rear of the third phalanges of the second, third and fourth toe and confined to the metatarsal dome, to the heads of the second, third and fourth metatarsal bones and extending slightly forward of said heads and the upper surface of said cushioned area provided with three shallow substantially equal elliptical depressions located respectively beneath the heads of the second, third and fourth metatarsal bones.

4. A shoe provided with a one piece cushion for the ball of the foot, said cushion provided on its upper side with three shallow depressions located beneath the heads of the three middle metatarsal bones, and on its lower side with three shallow protuberances, one located beneath each depression whereby the cushion is of substantially the same thickness in the portions containing the depressions and protuberances as in the portions therebetween thereby to provide substantially equal cushioning effect to the sole in the areas beneath the heads as in the spaces beneath the heads of the three middle metatarsal bones.

5. In a shoe, means providing a sole engaging surface and including a cushion in the region of the ball of the foot, said cushion provided

- initially in its upper face with a shallow elliptical depression located beneath and conforming substantially to the underside of one of the heads of the metatarsal bones of a size in plan not materially larger than the vertically projected outline of the associated metatarsal head and substantially flat in the region immediately in advance thereof underlying the associated ball joint of the foot and in the region immediately in rear thereof and said depression tending during use to conform to whatever variations in contour may be imposed thereon by the metatarsal head pressing down through the intervening tissue of the foot.
5. A shoe provided with an inner sole, a cushion on said sole at the ball portion of the shoe, said cushion being egg-shaped in plan with the wider end located beneath the heads of the middle metatarsal bones and its narrow end terminating approximately at the junction of the tarsal and metatarsal bones, the forward edge terminating approximately at the center of the middle proximal phalanges and having a curve approximating the curve in the horizontal plane formed by the heads of the metatarsal bones.
10. An inner sole for a shoe split in the region of the ball of the foot to form a hollow pocket with an integral extremely thin flap overlapping the pocket, a one-piece flat cushion fitted in said pocket and cemented to the flap, said cushion provided on its upper surface with a shallow recess substantially elliptical in plan located beneath a head of a metatarsal bone and 15 said flap being sufficiently thin and flexible to permit the sole of the user to press the flap into and thus take the contour of said recess.
15. A one-piece soft rubber pad for a shoe, said pad having substantially a flat segment of 20 egg form with its upper side provided with a shallow depression for receiving the head of the second metatarsal and extending lengthwise of the second metatarsal.
20. A foot corrective appliance consisting of 25 an integral piece of material having a convex top surface and provided with a recess for the head of the second metatarsal shaft, a recess for the head of the third metatarsal shaft, and a recess for the head of the fourth metatarsal 30 shaft, said recesses being of sufficient length to accommodate substantially the entire length of the respective metatarsal shaft heads, the end portion of the appliance being shaped so as to terminate beyond the distal heads of the metatarsal shafts.
25. A shoe provided at the ball of the foot with a sole engaging part provided on its upper face with five shallow recesses, one for each head of the five metatarsal bones and each located beneath and conforming substantially to the underside of its associated head and cushioning means of highly flexible material less than the width of the sole at the part thereof containing the recesses overlying said portion and disposed to leave the two outer recesses exposed and the underside of said cushion conforming to the portion of the sole which it engages.
30. A shoe provided at the ball of the foot with a pad provided on its upper face with five shallow recesses, one for each head of the five metatarsal bones, each located beneath its associated head, the three middle recesses contained within the outline of the pad and the two outer recesses being incomplete in outline and substantially bisected by the adjacent edge of the pad.
35. A shoe having its sole engaging portion at
- the ball of the foot formed at its mid-portion by a rubber cushion and on opposite sides of the rubber cushion by leather, the edge portion of the rubber cushion and the adjacent portion of the leather being recessed to form a shallow depression located beneath the head of one of the outer metatarsal bones.
40. An inner sole for a shoe split in the region of the ball of the foot to form a hollow pocket with an integral extremely thin flap overlapping the pocket, a one-piece flat cushion fitted in said pocket and cemented to the flap, said cushion provided on its upper surface with a shallow recess substantially elliptical in plan located beneath a head of a metatarsal bone and 45 said flap being sufficiently thin and flexible to permit the sole of the user to press the flap into and thus take the contour of said recess.
45. A one-piece soft rubber pad for a shoe, said pad having substantially a flat segment of 50 egg form with its upper side provided with a shallow depression for receiving the head of the second metatarsal and extending lengthwise of the second metatarsal.

BENJAMIN J. SILVER.
